UNITED STATES PATENT OFFICE.

HARRY C. GAMMETER, OF CLEVELAND HEIGHTS, OHIO.

PYROTECHNIC ALARM AND SYSTEM INVOLVING THE SAME.

Application filed April 8, 1926. Serial No. 100,751.

This invention relates to a pyrotechnic alarm, and more particularly to a system involving the same that is adapted to the protection of homes, banks, and other institutions, in that it provides a ready means of spreading an alarm throughout a neighborhood in case of fire, theft, burglary or other emergency wherein outside aid is desired at the source of trouble, or in apprehending the 10 escaping culprit.

The alarm or signal, per se, is similar to that disclosed in my copending application Serial No. 100,750 filed April 8, 1926, and entitled "Pyrotechnic signal," but the present 15 device is adapted to the system disclosed herein by reason of the fact that it is electrically operated and therefore can be set off from one or more remote points.

The primary purpose of the invention is to 20 provide an alarm of a pyrotechnic nature that is either automatically set off by an attempt of an unauthorized person to enter or gain access to an enclosure that is under the protection of the alarm, or which may be discharged at will upon the actuation of a secondary alarm which is automatically set in 25 operation by such an attempt; the pyrotechnic alarm preferably incorporating an aerial projectile and a flare, the former being thrown to a great height when the device is 30 set off and bursting with a heavy detonation that can be heard for a considerable distance and producing a brilliant pyrotechnic display by night and a dense cloud in daylight. 35 This serves both audibly and visually to attract attention to a general locality, and at night serves to illuminate the whole territory thus rendering more difficult the escape of the culprit in case of a theft, burglary or the like. 40 The flare, which continues to issue from the device for a considerable length of time after the aerial projectile has been discharged, serves to guide those whose attention has been attracted by the aerial projectile to the specific location of the trouble. The flare also 45 serves as a means of illumination.

Other and more specific objects of the invention are to provide a thoroughly reliable and efficient pyrotechnic device that retains 50 its operative condition indefinitely or until discharged and is always in readiness for use; to provide a device of the aforesaid character that is electrically operated; to provide, in combination with a pyrotechnic signal, a system whereby the signal may be set off from one

or more remote locations; to provide, in a system of the aforesaid character that is electrically operated, one or more circuit closers that is or are adapted to be automatically actuated by the intrusion of an unauthorized 60 person or persons into forbidden quarters; to provide in such a system means for rendering the same inoperative at will; and to provide a dual alarm system that is electrically operated and involves a source of energy, a pyrotechnic signal, an electrically energized signal, one or more circuit closers of the above 65 mentioned nature for automatically closing a circuit, and a plurality of circuits, preferably all having the same source of energy, by 70 which, through the operation of one of said circuit closures, either the pyrotechnic alarm is set off, or the electrically energized alarm is actuated, according to the position of a selective switch that is included in the system, and 75 by which, through the closing of another switch—in case the selective switch is set to effect the actuation of the electrically energized signal—the pyrotechnic signal is fired.

Objects additional to the foregoing will become apparent as I proceed to describe the embodiment of the invention illustrated in the accompanying drawings wherein Fig. 1 represents a side elevation of the electrically operated pyrotechnic signal or alarm; Fig. 2 80 is a central longitudinal section through the same; Figs. 3 and 4 are cross sections through the device on the respective lines 3—3 and 4—4 of Fig. 2; and Fig. 5 is a diagram serving to illustrate the system. 85

The pyrotechnic device is comprised of a base 1 to which is fitted one end of a barrel 2. The base has a bore that is shown as being incident to the axis of the barrel 2, and the inner end of the bore is enlarged and occupied 90 by a thimble 3. A tube 5 has its inner end fitted within the thimble 3 and projects a material distance into the barrel 2. The space between the barrel and tube is filled with a quantity of suitable flare producing material 95 designated 6, and said material is covered by a dished annual washer 8 that is pressed into the barrel 2 and held by friction. A patch 9 of suitable material, such as cloth, preferably impregnated with a highly inflammable substance, is inserted between the central portion of the washer 8 and the material 6 and extends over the top of the tube 5. 100

Pressed into the top of the barrel 2 above the washer 8 is an aerial projectile or detona- 105 110

tor 10, the same comprising a hollow core 11 that is filled with a suitable powder, and the core is encased within a heavy wrapping 12 of paper or the like. The projectile is enveloped by a sack 15 of cloth or other material appropriate for the purpose and across the lower open end of the sack is disposed a patch 16, similar to the one previously described and designated 9. The sack and patch 10 serve to support an impelling charge 17 of powder of suitable quality and the fire from said charge, or from the patch 16, is adapted to be communicated to the contents of the core 11 by powder contained in a tube 18 that 15 is inserted through the lower end of the projectile and extends substantially to the patch 16. To insure the fire reaching the contents of the tube 18, a fuse 19 is inserted through diametrically opposed holes in the tube, the 20 ends of the fuse being in juxtaposition to the patch 16. The space within the barrel above the aerial projectile is shown as filled with a body 20 of mineral wool or other suitable material which is readily dislodged by 25 the projectile. The end of the barrel may be closed by a cap 21.

Fitted within the thimble 3 below the tube 5 is a hollow plug 23 that contains a quantity of suitable highly inflammable substance 30 within which is embedded the terminals 25 of electrical conductors designated *a* and *b*. The terminals 25 are bridged by an igniter 26 that is fused when current is directed through it and sets fire to the surrounding 35 body of inflammable material. A fuse 28 occupies the tube 5 and at each end joins a deposit 29 of combustible material. Therefore, when the igniter sets fire to the inflammable material surrounding it, the fire is 40 communicated through the fuse 28 to the patch 9 which serves to distribute the ignition to the flare material 6 and to the patch 16 which, in turn, sets off the impelling charge 17 of the aerial projectile and ignites, through 45 the fuse 19, the powder within the tube 18 which serves to carry the fire to the contents of the core 10 during the ascent of the projectile.

The base, the barrel and the cap may be 50 made of any suitable material that will withstand prolonged exposure to the weather, and if, as in the instance of the pyrotechnic signals shown in my companion application hereinbefore referred to, the base is made 55 of wood and the barrel of heavy paper or cardboard, the parts are very thoroughly water-proofed. Also, the body 20 of mineral wool or the like which occupies the end of the barrel may be thoroughly filled with 60 paraffin. The cap 21 may be of a suitably protected metal.

In the diagram of Fig. 5, I have represented an installation of my alarm system that is suitable for residences, and from 65 this example it will be obvious how the sys-

tem may be employed in stores, manufacturing plants, banks and other institutions, the circuit closers being associated, in some instances, with vaults, safes, money drawers, cash registers and the like.

In the diagram, the pyrotechnic signal is designated generally by the reference letter A, and the source of electric energy is designated B and is conventionally shown as a battery. The current may flow from the source of energy through a conductor *a* to the signal, and return through the conductors *b* and *c* which are adapted to be connected by a switch C.

The pyrotechnic signal is located outside the building, preferably near or on the roof thereof, and as indicated in dot and dash line in Fig. 1, the same may be sustained by a bracket 30 that is attached to a suitable support 31, as a part of the building. It may be mentioned in this connection that in some instances I propose locating the signal just inside the exhaust end of the vent pipe of the dwelling where it is concealed from view yet from which location it will effectively serve its purpose. Located at a desired place within the building, as in a bed chamber, is a secondary alarm designated at D. This alarm may be in the nature of an electric buzzer or bell or, in some cases, it might be a light, or it may be a combination of a visual and audible signal. A selective switch E is located at a convenient place, as near an entrance door F, and said door is equipped with a circuit closer G, as are also the windows designated H, the circuit closers of the windows being represented conventionally at I. Of course, as many doors and windows may be equipped with circuit closers as is desired or thought necessary.

When the selective switch E is thrown to the position designated X, current is adapted to flow from the source B, through the conductors *a* and *d*, alarm D, conductor *e*, switch E, conductors *f*, and *f'* or *f''*, circuit closers I or G and conductors *g* or *g'* to the source. Thus, if the door or either of the windows is opened while the selective switch occupies position X, the alarm D will be energized whereupon a person hearing it may close 115 switch C and thus set off the pyrotechnic signal by the fusing of the igniter 26. The secondary alarm is employed for notifying those in the home that a door has been opened or an attempt has been made to gain entrance through a window by an unauthorized person and it has the advantage over directly connecting the circuit closers to the pyrotechnic alarm of avoiding the firing of the same by an accidental actuation of the circuit closers by a proper opening of a door or window.

On the other hand, when the occupants of the home are away, it is desirable then that the pyrotechnic signal be sounded if any one 130

attempts to enter the building. To accomplish this, the switch *E* is turned to position *Y* whereupon a circuit is established from the source of energy through the conductor *a*, signal *A*, a part of the conductor *b*, conductor *h*, switch *E* and thence through one of the branches previously described including one of the circuit closers, to the source.

Having thus described my invention, what I claim is:

1. A pyrotechnic alarm comprising a base, a barrel surmounting the base, a quantity of flare material within said barrel, an aerial projectile and its impelling charge within the barrel in advance of said flare material, an electric igniter in the base, and means for communicating fire therefrom to the impelling charge of the aerial projectile and to the adjacent end of the quantity of flare material.
2. A pyrotechnic alarm comprising a base, a barrel surmounting the base, a quantity of flare material within said barrel, an aerial projectile and its impelling charge within the barrel in advance of said flare material, an electric igniter in the base, means for communicating fire therefrom to the impelling charge of the aerial projectile and to the adjacent end of the quantity of flare material, and a cap removably applied to the end of the barrel.
3. A pyrotechnic alarm comprising a base, a barrel surmounting the base, a quantity of flare material within the barrel, an aerial detonator and its impelling charge within the barrel in advance of said flare material, said detonator involving an explosive charge, means for communicating the ignition of the impelling charge to the explosive charge, an electric igniter within the base, and means for communicating fire therefrom to the impelling charge of the detonator and to the adjacent end of the quantity of flare material.
4. A pyrotechnic alarm comprising a base, a barrel surmounting the base, a tube extending from the base a distance into the barrel, a quantity of flare material occupying the space between the tube and barrel, an aerial projectile and its impelling charge occupying
5. A pyrotechnic alarm comprising a base having a bore, a barrel extending from the base and into which the bore of the base opens, a thimble inserted within the end of said bore adjacent the barrel, a tube projecting from the thimble a suitable distance into the barrel, a quantity of flare material occupying the space between the tube and the barrel, an aerial projectile and its impelling charge within the barrel in advance of said quantity of flare material, an electric igniter within the thimble and adjacent the end of said tube, a fuse extending through the tube for communicating fire from the igniter to the impelling charge of the projectile and to the adjacent end of the quantity of flare material.
6. A pyrotechnic alarm comprising a base, a barrel secured to and extending from the base, the base having a substantially central bore that opens into the barrel, a tube extending from said bore a suitable distance into the barrel, a quantity of flare material filling the barrel about said tube, a fire communicating patch overlying the end of the tube and the adjacent end of said quantity of flare material, a member disposed above said quantity of flare material, said member having an aperture through which a portion of the patch is exposed, an aerial projectile and its impelling charge enclosed within a sack and occupying the portion of the barrel beyond said member, said sack having an opening opposite the opening in said member, a patch of fire communicating material closing said opening, a fuse extending through said tube, and an electrical igniter within the base in operative relation to the adjacent end of said fuse.

In testimony whereof, I hereunto affix my signature.

HARRY C. GAMMETER.
